J. WHITELEY

AMUSEMENT DEVICE

Filed Feb. 21, 1924

INVENTOR.
JAMES WHITELEY
BY
Edmund A. Tracy
ATTORNEY.

UNITED STATES PATENT OFFICE.

JAMES WHITELEY, OF NORTH TONAWANDA, NEW YORK.

DESIGN FOR AN AMUSEMENT DEVICE.

Application filed February 21, 1924. Serial No. 8,696. Term of patent 7 years.

To all whom it may concern:

Be it known that I, JAMES WHITELEY, a citizen of the United States, residing at North Tonawanda, in the county of Niagara, and State of New York, have invented a new, original, and ornamental Design for an Amusement Device, of which the following is a specification, reference being had to the accompanying drawings, forming a part thereof.

Fig. 1 is a side elevation of an amusement device, showing my new design.

Fig. 2 is a perspective view of the amusement device shown in Fig. 1.

I claim:

The ornamental design for an amusement device, as shown.

JAMES WHITELEY.

Witnesses:

EDMUND A. STRAUSE,
PAULINE K. GANSER.
